UNITED STATES PATENT OFFICE

CHARLES C. MEUTSCH, OF BUFFALO, NEW YORK

SPRING STRUCTURE

Application filed June 9, 1928. Serial No. 284,256.

This invention relates to a spring structure and method of producing the same, and more particularly to such a structure which is particularly adapted for use in furniture and automobile upholstery, mattresses, cushions and the like, and in which helical springs are employed each of which is housed within an independent separate cloth pocket or housing and a number of springs and their 10 housings are arranged side by side to form a group of springs which yieldingly support the upholstery.

One of the principal objects is to provide an independent individual housing for each 15 of the helical springs by means of which the springs and their housings may readily be arranged to form a spring structure of any desired configuration. Thus if it is necessary to leave a void in the structure to accommodate an arm or other part of the furniture frame the individually housed springs can be left out in this place. By this means the assembly of spring structures in odd shapes is greatly facilitated.

25 A further object is to substitute for the burlap backings generally employed in housed spring structures, a plurality of cords which extend across the spring structure and diametrically across the ends of the individual spring housings and tie the corresponding edges of the housings together. Such a method of tying the structure together has been found to be markedly superior to the usual burlap backing in point of 30 wear and in addition permits individual housings to be cut away from the rest of the group without alteration of the rest, when a completed structure is being fitted to an irregular shaped piece of furniture or the like.

40 Furthermore, tying of the springs by means of cords in contradistinction to sewing them on burlap eliminates the necessary marking of the burlap and also greatly facilitates the operation of assembling a spring structure by 45 eliminating the sewing operation.

Individually housed springs also lend themselves more readily to use on rounded surfaces such as the curve of the upholstered arms of a lounge since they can be readily 50 tied to conform to the curvature thereof.

A still further aim is to provide such a housing which can be quickly, readily and accurately sewed with an expenditure of a minimum amount of time, labor and material, thereby permitting of producing the 55 structure at low cost.

Another purpose is to provide such a housing or pocket which is readily filled with its spring and when so filled operates reliably to retain it therein.

Another aim is to provide such an individual, independent housing in which the end coils of the spring bear against a double thickness of material thereby greatly increasing the wear of the pocket.

Other purposes are to provide such a spring structure which will provide a comfortable cushion and which will withstand severe conditions of wear without alteration in its condition.

In the accompanying drawings:

Figure 1 is a perspective view of a spring structure made in accordance with my invention and showing the same slightly compressed. Figure 2 is a cross section through one cloth pocket or housing showing a spring arranged therein. Figure 3 is a fragmentary transverse section through a pair of pockets, the section being taken on line 3—3, Fig. 2. Figures 4—7 are perspective views showing successive stages in the sewing of the cloth pockets. Figure 8 is a vertical section through the back of an upholstered chair, showing the manner in which a structure made in accordance with the present invention is adapted to furniture in which the cover is buttoned to the frame at intervals.

Similar reference numerals refer to like parts in each of the several views.

In its general organization the present invention is composed of a group of upholstery springs each housed within an individual independent cloth pocket or housing and the group of housed springs being joined by a plurality of cross cords on opposite sides of 85 the structure which cross cords are tied to each of the housed springs at each quarter.

Each of the cloth housings or pockets, indicated generally at 10, is made of two cloth strips which are sewed and folded in the 100

manner shown in Figs. 4-7, this operation being as follows:

A strip of cloth 11 is marked into lengths as indicated at 12 and between these marks is provided with gage marks 13 which divide the strip into three parts, a bottom part 11^a, a short end 11^b, and a long end 11^c. A second strip of cloth 14, of the same length as the lengths of the strip 11 is then folded over to form a loop and its opposite ends are brought together and placed along one edge of the strip 11, the loop extending transversely across the strip 11, as best indicated in Fig. 4. The strips are then run through a sewing machine and the ends of the strip 14 are sewed to the edge of the strip 11 by stitches 15. In production, the sewing is continued along the edge of the strip 11 and the operator of the sewing machine places the strips 14 in proper relation before the needle passes over the marked part 11^a. The strip 11 is then cut into lengths along the marks 12.

The strip 14 has previously been marked as indicated at 16 so as to demarcate two side parts 14^b and 14^c and an upper central part 14^a at one side of which the strip is folded. The loop formed by the strip 14 is now opened up, as indicated in Fig. 5 so that a bottom part 14^a lies on the bottom part of 11^a of the strip 11, the sides 14^b and 14^c rise from the edges of the strip 11 and the upper part 14^a is arranged horizontally.

The short end 11^b of the strip 11 is then brought up and its end arranged under the corresponding edge of the upper part 14^a as shown in Fig. 6. Thereafter the long leg 11^c is brought up and over the upper part 14^a and its end placed in alinement with the opposite edge of the upper part 14^a of the strip 14. The pocket is then sewed, the stitches 17 passing through the ends of the strip 11 and the edge of the upper part 14^a of the other strip.

The upholstery spring 18 is then compressed and passed through one of the four openings at the corners of the pocket. The spring is then placed in proper position and released, the ends of the spring bearing against the upper and lower parts 14^a and 14^b of the pocket which are reinforced by the upper and lower parts 11^a and 11^b which overlay and are secured to these parts. By this means it will be noted that by two sewing operations an individual pocket is provided which has reinforced ends and full flexibility at its sides. Moreover, the operation of making the pocket is extremely simple and can be done rapidly and efficiently by one not particularly skilled at such work.

In using the springs in upholstered furniture, mattresses or the like, the several springs are tied together and placed in the center of the mattress or on the supporting frame of the furniture. In Fig. 8 is illustrated a conventional form of chair back composed of a

wooden frame 19, back webbing 20 supporting main back springs 21, and burlap coverings 22 and 23 over the webbing and the springs.

The spring structure forming the subject matter of the present invention is adapted to impart greater softness and is placed over the burlap cover 23, the upper end of the spring structure being curved over the upper side of the chair frame. The usual stuffing 24 is then placed over the spring structure and the whole covered by the usual cover 25.

To form the spring structure, the several individual, independent spring pockets are grouped together as shown in Fig. 1 so that they are in alinement in both directions. A cord or string 26 is passed through the outer side of one of the marginal pockets and under the outermost coil of the spring 18 therein.

The cord 26 is then tied at this point as best shown in Fig. 3 and is passed diametrically over the pocket and is passed through the corners of the adjacent pockets, around the corresponding end coils of the springs thereon and tied, thereby securely tying the two pockets and the spring therein. In a similar manner, a complete row of spring pockets are tied together, the row being tied at its opposite or under side in the same manner by cords 26^a. The several rows are then tied together in the same manner by cords 27 and 27^a which are arranged at right angles to the first cords and tie the spring pockets in transverse rows.

If a spring structure of irregular outline is desired, it is apparent that any number of the spring pockets 10 may be left out to make the structure conform to the desired shape. Thus, as shown in Fig. 1, if it is desired to have the structure fit about a projecting arm or the like, the spring pockets may be left out to form an indented corner or side. If also, in making furniture in which the cover is "buttoned" down at spaced intervals to form a pillow'd surface instead of the usual smooth upholstered surface, one of the spring pockets 10 at the center of the structure can readily be left out and the cover drawn into the void left thereby. Such a construction is indicated in Fig. 8 in which one of the spring pockets 10 has been left out at the center of the structure and the cover drawn into the void left thereby and secured to the burlap backing 23 by means of a button 28.

It is apparent that such irregularities may be provided for either by leaving the spring pocket out in the course of manufacture, or the same may be cut out after the spring structure is assembled. In the latter case the spring pocket or pockets to be removed are cut free without disturbing the rest of the structure.

If it is desired to have the structure curve, as indicated in Fig. 8 in which the structure curves around the back of the chair, one set of

5 cords is tied so as to leave a length of cord 29 between the rows of pockets at the place where the structure curves, the cord being tied to each pocket at the places where it crosses the pocket. By this means, the desired softness in the upholstery is provided at such places and the pockets are securely held against displacement by a full cord support.

10 As a whole this invention is very simple in construction, it can be readily adapted to irregular forms either in making the same or after the same has been made up, the independent individual pockets are readily and 15 inexpensively fabricated and the complete structure can be produced at low cost and requires relatively unskilled labor to produce the same.

I claim as my invention:

20 1. An independent, individual cloth housing for a helical spring comprising two cloth strips arranged at right angles to each other, the ends of one of said strips being sewed to an intermediate part of the other strip and 25 the ends of said last named strip being sewed together to form a loop.

25 2. An independent, individual cloth housing for a helical spring comprising two cloth strips arranged at right angles to each other, 30 the ends of one of said strips being sewed to an intermediate part and along one edge of the other strip, and the ends of said last named strip being sewed to an intermediate part and along one edge of the first named 35 strip thereby to form two loops which are united at their opposite ends and are adapted to enclose the spring.

3. An independent, individual cloth housing for a helical spring comprising two cloth 40 strips of substantially equal length, the ends of one of said strips being sewed to an intermediate part and along one edge of the other strip, and the ends of said last named strip being sewed to an intermediate part and 45 along one edge of the first named strip, said strips thereby forming two loops adapted to receive the spring and being arranged to form double thickness parts against which the end coils of the springs bear.

50 4. A method of forming an individual, independent cloth housing for a helical spring comprising sewing the ends of each of a plurality of cloth strips at spaced intervals along another strip, cutting said last named strip 55 into lengths substantially equal to the length of each of said first named strips, each of said lengths having one of said first named strips secured thereto; and thereafter sewing the ends of the last named lengths of strip to an 60 intermediate part of the loop formed by said first named strip.

5. A method of forming an independent cloth housing for a helical spring comprising sewing the ends of each of a plurality of cloth 65 strips at spaced intervals along another strip,

cutting said last named strip into lengths substantially equal to the length of each of said first named strips, each of said lengths having one of said first named strips secured thereto; and sewing the ends of said last named lengths of strip to one edge of the loop formed by said first named strip.

6. A method of forming an independent cloth housing for a helical spring comprising folding a strip of cloth and placing it at right angles over another strip of cloth so that the ends of said folded strip are arranged along one edge of the other strip and the loop thereof extends across said last named strip, sewing the ends of said folded strip to the edge of said last named strip, placing the ends of said last named strip on opposite sides and at one edge of an intermediate part of said folded part and sewing the ends of said last named strip to the intermediate part of said folded strip.

In testimony whereof I hereby affix my signature.

CHARLES C. MEUTSCH.
